UNITED STATES PATENT OFFICE.

JAKE JONES, OF ST. LOUIS, MISSOURI.

RAILROAD APPLIANCE.

1,414,814.

Specification of Letters Patent. Patented May 2, 1922.

Application filed February 25, 1921. Serial No. 447,694.

To all whom it may concern:

Be it known that I, JAKE JONES, a citizen of the United States, and resident of St. Louis, Missouri, have invented certain new and useful Improvements in Railroad Appliances, of which the following is a specification.

This invention relates to improvements in railroad appliances, and has for its object 10 the combination of a combined car replacer and wheel-shoe by which de-railed cars may be readily and quickly replaced on the rails with little labor and loss of time and by which broken or otherwise disabled wheels 15 may be speedily equipped with a shoe thereby permitting the disabled car to be conveyed over the rails in order to rapidly clear the right-of-way.

A further object of my invention is to construct a device which can be used as a car replacer as well as a shoe for supporting a disabled wheel and when the same is applied as a shoe the interior is filled with water so as to properly cool the shoe while the same is 25 being drawn over the rail so as to prevent the shoe from becoming over-heated by the frictional contact.

The invention consists preferably of two members, one being a combined replacer and 30 shoe and thoroughly illustrated in Figs. 1 to 6 inclusive, while the other is a replacer itself which is provided with a suitable hump on its curvilinear surface and by which the wheel is slid in place on the rail.

35 Figure 1, is a top plan view of my combined replacer and shoe.

Fig. 2, is a front view of the same.

Fig. 3, is a central sectional view of the same.

40 Fig. 4, is a central cross sectional view.

Fig. 5, is an end view showing the same in the position for replacing the truck on the rail.

45 Fig. 6, is a sectional view showing my device in application as a shoe for supporting the wheel to the rail.

Fig. 7, is a top plan view of the replacer.

Fig. 8, is a front view of the same.

Fig. 9, is a central cross sectional view.

50 Fig. 10, is an end view showing the same in position for replacing the truck on the rail.

Fig. 11, is a perspective view.

55 Fig. 12, is a view showing the end wheels of a railroad truck with the replacer in po-

sition and in the act of replacing the wheels on the rails.

In carrying out my invention I construct a means whereby derailed cars may be readily and rapidly replaced on the rails and 60 in order to accomplish the required result the two members as illustrated work in conjunction and are placed in position on the ties and against the rails as that illustrated in Fig. 12.

65 The most important feature of my invention is the combination of the replacer and shoe as illustrated in Figs. 1 to 6 inclusive and it consists of a suitable casting having two side walls 13 and 14, the wall 13 70 being of a higher construction than the wall 14, the two walls being connected together by a peripheral surface 15 and terminating into a flange 16, the ends of the peripheral surface are suitably flanged as that indicated 75 by the numeral 17 and are provided with a perforation or hole 18 through which a chain or other fastening device may be inserted so that the casting when used as a shoe for supporting a crippled wheel can 80 be properly fastened to the body of the car or truck in order to hold the same in position as that shown in Fig. 6.

85 The side walls 13 and 14 are suitably provided with a flanged surface 19 from which radiate spurs 20. These spurs are designed to be brought in contact with the ties 21 so as to sink therein sufficiently when pressure is applied on the shoe so as to prevent the shoe from slipping when the same is used as 90 a replacer.

95 The relative position of the shoe as a replacer in conjunction with the rail is clearly illustrated in Fig. 5.

100 The inner surface of the casting is provided with a plurality of ribs 22, these ribs are of a sufficient height to support the tread 23 of the car wheel 24, as well as to provide sufficient space for water to flow beneath the tread as well as to strengthen the casting. This surface at the ends of the ribs 25 terminates into a depression 26 which is to accommodate the flange 27 of the wheel.

105 When this device is to be used as a shoe for conveying a crippled wheel and can be rapidly rolled on the rail the same is placed on the rail as that shown in Fig. 6, and fastened in position by the chains 28 or fastening devices to the truck then the shoe is slid along on the rail so that the car can be 110

conveyed to a siding in order to prevent over-heating of the shoe by its sliding frictional contact a quantity of water is placed in the shoe as that shown in Fig. 6, this 5 will cool the shoe and preserve the same. The other member which is necessary to operate in conjunction with the shoe consists of a casting comprising two walls 29 and 30 and a curvilinear or convex connecting surface 31, these walls being one higher than the other and the free ends of the walls are suitably flanged and provided with spurs 32 which contact with the ties. This replacer is provided with a hump 33 which is of an 10 inclined construction and so arranged that when the flange of the wheel when rolling up on the convex surface 31 will cause the wheel to slide down the incline and place the wheel back in position on the rail. This 15 position of the replacer relative to the rail and wheel is clearly shown in Fig. 10. This replacer is suitably re-inforced for strength by means of a plurality of cross ribs 34 extending from wall to wall and varying in 20 height to provide sufficient rigidity owing to the weight of the car as the same is being pulled upon by the replacer.

These devices are constructed are such length as to properly span two ties and the

inner concave surface of the combined replacer and shoe is of a radius sufficiently large to accommodate the size of a standard car. 30

Having fully described my invention what I claim is:

A railroad appliance comprising two castings, one to be placed on the outside of one rail and the other on the inside of the other rail, each casting consisting of a body member having a semi-circular periphery, the 35 surface thereof tapered from a low wall to a high wall, a flange formed on the peripheral surface of the high wall, transverse ribs located in the body connecting the low and high walls of the inside casting and extending from the low wall to the groove in the outside casting, both of said bodies to be used simultaneously in conjunction with replacing a de-railed truck on to the rails, substantially as specified. 40

45 In testimony whereof, I have signed my name to this specification, in presence of two subscribing witnesses.

JAKE JONES.
